UNITED STATES PATENT OFFICE.

EDWARD A. LANGENBACH, OF CANTON, OHIO.

DESIGN FOR A MITER-PIECE.

SPECIFICATION forming part of Design No. 24,428, dated June 25, 1895.

Application filed May 23, 1895. Serial No. 550,453. Term of patent 7 years.

To all whom it may concern:

Be it known that I, EDWARD A. LANGENBACH, a citizen of the United States, and a resident of Canton, county of Stark, State of Ohio, have invented a new and useful Design for a Miter-Piece for Metallic Sidings, of which the following is a full, clear, and exact description, reference being had to the accompanying drawings, making part of this specification.

My invention relates to a design for a miter piece for metallic ceilings.

In the accompanying drawings, Figure 1 is a front elevation of a miter-piece made in accordance with my design. Fig. 2 is a central vertical section of the same.

My design consists essentially in a miter piece of the shape or configuration shown in the accompanying drawings, and comprises a leaf-shaped piece, A, curved lengthwise and transversely, and tapering from the stem or lower portion to the point. The piece at the lower end is formed with two curved extensions, B B, provided near the edges with ornamental scroll work, C, and at the center formed with an ornamental leaf-shaped portion, D, having a row of circular projections, E. The miter piece above the said extensions is made

up of a number of ornamental segments, F, having scalloped edges, G, and is also formed with a row of circular projections, H, which gradually decrease in size from the lower to the upper one. At each side of this row of projections is a curved rib, I, extending from about the center of the piece to the lower end, and the end of each of these ribs is connected with a circular projection, K.

The leading features of the design are the curved leaf-shaped miter piece, made up of a number of ornamental segments with scalloped edges, the central row of circular projections gradually decreasing in size, the rounded extensions ornamented by scroll work, the leaf-shaped portion at the lower end formed with curved projections and the curved ribs and the projections connected therewith.

What I claim is—

The design for a miter piece herein shown and described.

In testimony whereof I have hereunto set my hand this 17th day of May, A. D. 1895.

EDWARD A. LANGENBACH.
